TRIGGER FOR HIGH RATE ACTUATORS
John H. Gavin, 105 Savo Ave., Lancaster, Pa.
Filed Jan. 17, 1964, Ser. No. 338,515
12 Claims. (Cl. 60—51)

This invention relates generally to high rate pressure operated actuators and more particularly to such actuators incorporating novel and improved self-triggering means arranged to prevent loss of the pressurizing fluid.

High energy actuators are used for a number of purposes one of the principal of which is die forming of metal parts and the like. In such forming devices a plunger is accelerated by gas under substantial pressures to carry a die with high impact velocity against the material to be formed. In an actuator incorporating this invention, improved triggering means are provided to hold the plunger in the cocked position which are arranged so that a substantially instantaneous release of the plunger occurs without the loss of any charging fluid.

An actuator to which this invention is particularly suited includes a cylinder or housing with a plunger slideable therein between a cocked or first position and an operated or second position. The plunger and cylinder cooperate to define a closed cavity charged with fluid under pressure. When the plunger is moved to the cocked or first position the pressure of the fluid in the cavity increases to a relatively high-pressure. The plunger and cylinder are provided with mating surfaces which engage and seal to isolate a chamber from the main cavity when the plunger is in the cocked position and means are provided to reduce the pressure in this isolated chamber without loss of fluid to hold the plunger in its cocked position. The effective area of the isolated chamber is greater than the effective area of the plunger within the main cavity so that a pressure induced force is created holding the plunger in its cocked position. When the plunger is to be triggered the isolated chamber is pressurized, causing the plunger to move away from the cocked position and provide complete communication between the chamber and cavity. This produces an almost instantaneous elimination of the balancing area and results in extremely high accelerations of the plunger toward the operated or the second position.

In the past actuators have been provided of this general character wherein the plunger is moved to the cocked position and the isolated chamber vented to reduce its pressure. This resulted in a loss of fluid under pressure each time the actuator was operated. In an actuator incorporating the present invention means are provided to increase the volume of the isolated chamber thereby reducing the pressure therein without loss of any of the charging gas. Therefore, it is not necessary to supply additional charging gas as the machine is operated.

It is an important object of this invention to provide a fluid pressure operated actuator incorporating novel and improved triggering means arranged so that the charging gas in the actuator is not lost during the operation of the triggering mechanism.

It is another important object of this invention to provide a novel and improved fluid pressure actuator having a chamber adapted to be isolated from the main cavity of the actuator when the plunger or output member is in the cocked position in combination with means to reduce the pressure of the chamber to hold the plunger in the cocked position without loss of the fluid under pressure originally contained therein and incorporating means to automatically return the system to its initial condition.

Another important object of this invention is to provide a high rate actuator having improved triggering means and wherein the effective area of the piston is not changed during the operation.

2

It is still another object of this invention to provide an actuator incorporating a housing and plunger cooperating to define a variable volume cavity filled with charging fluid under pressure and cooperating when the plunger is in the cocked position to isolate a chamber from the cavity wherein means are provided to increase the volume of the chamber to reduce the pressure thereof to retain the plunger in the cocked position without loss of any of the charging fluid.

10 It is still another object of this invention to provide a triggering actuator incorporating a housing and plunger provided with means to isolate a triggering chamber from the main pressurized cavity wherein an accumulator is connected by valved means to the triggering chamber to allow reduction of the pressure in the triggering chamber and thereafter return the fluid to the actuator.

15 It is another important object of this invention to provide an actuator including a housing and slideable plunger cooperating to define a main cavity and a triggering chamber isolated therefrom when the plunger is in a cocked position wherein novel and improved valved means are provided to control fluid flow between the chamber and the cavity so that the pressure in the chamber can be reduced to retain the plunger in its cocked 20 position and thereafter increased to cause the plunger to be released.

25 Another object of this invention is to provide an actuator according to the preceding object wherein the valve means includes a check valve allowing fluid flow only from the chamber to the cavity and a normally closed triggering valve operable to permit flow from the cavity to the chamber.

30 Further objects and advantages will appear from the following description and drawings wherein;

35 FIGURE 1 is a schematic illustration of one preferred embodiment of this invention wherein an external accumulator is provided which is adapted to be connected to the triggering chamber to increase the volume thereof and reduce the pressure therein without loss of charging 40 gas;

45 FIGURE 2 is an enlarged fragmentary schematic illustration of a second embodiment wherein a single valve is provided which is operated to exhaust gas from the triggering chamber and thereafter admit gas to release the plunger;

50 FIGURE 3 is an enlarged fragmentary schematic illustration of a third embodiment illustrating the position of the elements when the plunger seal first engages the bore and the housing to isolate the triggering chamber from the main chamber;

55 FIGURE 4 is a view similar to FIGURE 3, illustrating the plunger at the top extreme position;

FIGURE 5 is a view similar to FIGURES 3 and 4, 60 illustrating the position of the elements after the plunger has dropped down to increase the volume of the triggering chamber thus reducing the pressure contained therein;

FIGURE 6 is a fragmentary schematic illustration of a 65 fourth embodiment of this invention utilizing an internal accumulator including a floating piston for increasing the trigger chamber volume to decrease the pressure therein illustrating the elements at the moment the plunger seal engages the mating wall in the housing; and,

FIGURE 7 is a schematic illustration similar to FIGURE 6 illustrating the floating piston in its retracted position in which the pressure in the trigger chamber is reduced.

Referring to the drawings, FIGURE 1 schematically illustrates a forming press incorporating one embodiment of this invention. The main frame 10 includes a base 11, a cylindrical frame member 12, and an end cap 13. Intermediate of its ends, the frame member 12 is formed

with an inwardly extending flange 14 which slidably engages a plunger or piston 16. A seal 17 on the flange 14 engages the outer surface of the plunger 16 and prevents leakage between the plunger 16 and flange 14. A seal 19 is mounted on the cap member 13 in engagement with the inner wall of the frame member 12 to prevent leakage therebetween. The plunger 16 in cooperation with the frame member 12 and cap 13 defines a main cavity 18 the volume of which is changed by movement of the plunger 16 relative to the frame 10.

The cap 13 is formed with a centrally located blind bore 21 open to the chamber 18 and closed at its upper end by an end wall 22. A flaring entrance 23 is formed at the open end of the bore 21 to facilitate the entry of a head 24 formed on the plunger 16. The head 24 is formed with a diameter proportioned to closely fit the wall of the bore 21 and is provided with a seal 26 to provide sealing engagement therebetween when the plunger is moved to the upward illustrated position. The upper end of the head 24 is formed with a taper 27 to facilitate the entrance of the head into the bore 21.

When the plunger 16 is in the upper position with the seal 26 engaging the wall of the bore 21, a triggering chamber 28 is defined by the head 24 and cap member 13 which is isolated from the cavity 18. Fluid under pressure is maintained in the cavity 18 by a charging mechanism described below. Normally the cavity 18 is charged to a predetermined pressure when the plunger 16 is in the cocked position of FIGURE 1. This insures that the desired pressure is available for operation.

When the plunger reaches the upper extreme position illustrated, the chamber 28 is isolated from the main cavity 18. The effective volume of the chamber is then increased to reduce the pressure therein to a pressure sufficiently low to cause the plunger to be retained in the cocked position by the pressure forces. The fluid under pressure in the cavity 18 then produces a force on the plunger 16 which is equal to the pressure times the difference in the effective area of the head 24 and the shank portion of the plunger extending through the seal 17. The effective area of the head 24 is equal to the area of the bore 21 and is proportioned to be larger than the area of the plunger extending through the seal 17. Therefore, the fluid under pressure produces an upward force on the plunger 16 which overcomes the weight of the plunger and retains it in the upward position so long as the pressure in the chamber 28 is maintained below the pressure in the cavity 18 by an amount sufficient to produce a pressure unbalance great enough to overcome the weight of the plunger 16.

A first pressure line 29 is connected through the end wall 22 to the chamber 28. This pressure line connects to an accumulator valve 31 and a triggering valve 32. The accumulator valve 31 is connected through a second pressure line 33 and to an accumulator 34. The accumulator 34 is provided with a cylindrical body 35 and a sliding piston 37 which is movable in the body 35 in response to differential pressures thereacross. The piston 37 operates to divide the accumulator into an upper gas-receiving chamber 38 and a lower liquid-receiving chamber 39. A pump 41 is provided to pressurize the liquid chamber 39. The intake of the pump is connected to a reservoir 42 and the output is connected to a valve 43 which can be selectively operated to supply liquid under pressure from the pump 41 to the chamber 39, or exhaust the chamber 39 to the reservoir 42.

The triggering valve 32 is connected through a pressure line 44 to the main cavity 18 and also through a line 45 to a charging valve 46. The charging valve 46 is in turn connected to a reservoir 47 of charging gas maintained under pressure by a motor-driven pump 48.

A pair of hydraulic jacks are provided to lift the plunger 16 to its cocked position illustrated in FIGURE 1. These jacks are preferably simple piston and cylinder

actuators having cylinders 49 in the base 11 symmetrically located with respect to the plunger 16. Each actuator is provided with a piston 51 engageable with the lower end face 52 of the plunger 16. Each of the cylinders 49 is connected in parallel to a four-way valve 53 by suitable piping and is supplied with operating pressure by a pump 54. The intake of the pump 54 and the exhaust of the valve 53 are connected to a reservoir 56.

The pistons 51 are double acting so that they may be extended to push the plunger 16 to the cocked position and then retracted by operation of the four-way valve 53 so that they are clear of the lower end of the plunger 16. Suitable dies may be mounted on the lower end face 52 of the plunger 16 and the upper end face 57 of the base 11. These dies have not been illustrated since they form no part of this invention. Normally, however, they are arranged so that downward movement of the plunger 16 causes the dies to work or form the desired article when the plunger causes the upper die to impact the material at a high rate of velocity. Suitable shock absorbing devices 58 are provided to support the entire system.

The valve 46 may be manual or automatic to supply any required make-up gas from the reservoir 47 to the cavity 18 when the plunger 16 is in its operated position since the pressure in the cavity is lowest in this position. Nitrogen is often used as a charging gas, however, other suitable gases may be used. In this way the charge in the chamber 18 is maintained at the desired minimum value. It should be realized that when the impact energy is to be changed, the pressure of precharge should be raised or lowered for such an adjustment. The valve 46, if automatic, should be such that backflow is prevented as the plunger 16 is raised, increasing the pressure in the cavity 18.

In operation, with the valve 31 closed and the triggering valve 32 open, the control valve 53 is operated to extend the pistons 51 and raise the plunger 16 against the pressure in the cavity 18 until the plunger reaches the uppermost position as illustrated. At the moment the seal 26 engages the lower end of the bore 21 the pressure in the chamber 28 is equal to the pressure in the cavity 18 so the seal 26 can smoothly move into engagement with the wall of the bore without damage. Preferably this occurs before the plunger reaches its uppermost position.

Continued upward movement after the seal 26 engages the bore 21 decreases the volume of the chamber 28 and causes gas to flow through the triggering valve maintaining the pressure in the chamber 28 and cavity 18 equal. Once the plunger reaches the fully cocked or upward position illustrated, the triggering valve 32 is closed and the accumulator valve 31 is opened. During this time the valve 43 is operated to permit exhaust from the chamber 39 to the reservoir 42, and the pump 41 is either by-passed or shut off. Since the pressure in the chamber 39 is maintained at substantially atmospheric pressure, the piston 37 will move down under the influence of the pressure in the chamber 28 as soon as the accumulator valve 31 is opened. This increases the effective volume of the chamber 28 and reduces the pressure therein. The capacity of the accumulator 34 must be sufficiently great to produce a reduction in pressure in the chamber 28 so that the fluid forces on the plunger 16 will produce sufficient upward force to overcome the weight of the plunger. At this time the plunger 16 is retained in its upper position by the fluid pressure forces and the valve 53 is operated to retract the pistons 51. The valve 31 is then closed to prevent overpressurization of the accumulator 34 when the triggering valve is opened to actuate the plunger 16. When it is desired to operate the press the triggering valve 32 is opened to permit flow from the cavity 18 into the chamber 38 thereby increasing the pressure in the chamber 28. This removes the balancing fluid forces and causes downward movement of the plunger carrying the seal 26 out of engagement with the wall of the bore 21 so that the chamber 28 is no longer isolated.

75

from the main cavity 18. Therefore, the gas under pressure in the main cavity 18 acts on an effective area equal to the area within the seal 17 to produce a high accelerating force on the plunger which carries it down to its operated position. Since high pressure in the chamber 18 acts on a relatively large effective area, the plunger very rapidly accelerates to produce a very high impact energy.

After the plunger reaches the lower most position, the valve 43 is operated to connect the output of the pump 41 to the accumulator chamber 39 and the valve 31 is opened to connect the chamber 32 to the cavity 18. The pump operates to supply sufficient pressure to move the piston 37 up to its initial position, thus returning any charging gas to the system. As soon as the piston 37 reaches its upper position, the valve 31 is closed and the system is back in its initial condition with all of the charging gas returned to the cavity 18. Therefore, no charging gas is lost during the operation of the system. Make-up gas therefore must only be provided to replace leakage which is very small. This invention thus eliminates any loss of charging gas during normal cycling of the system and operating costs of the mechanism are reduced.

In FIGURE 2 a second embodiment of this invention is illustrated which eliminates the need of a separate accumulator. In this figure only the triggering portion of the system is illustrated. It should be understood, however, that the frame 10 and actuators for pushing the plunger up to the cocked position would be identical with the embodiment of FIGURE 1. Corresponding reference numerals are utilized in the second embodiment to indicate similar parts to the embodiment of FIGURE 1, but an "a" is added to indicate the fact that the reference is to the second embodiment of FIGURE 2.

The cap member 13a in this embodiment is again formed with a blind bore 21a; however, the depth of the bore is deeper than in the first embodiment. Here again, a flaring entrance 23a is provided to facilitate the entrance of the head 24a of the plunger 16a. The seal 26a engages the wall of the bore 21a when the plunger 16a is a substantial distance from the upper extreme of its travel, thus isolating the chamber 28a from the main cavity 18a at a point in the stroke of the plunger well before the uppermost extreme position. The triggering valve 32a provides a fluid connection between the chamber 28a and the cavity 18a when it is open and isolates the two when it is closed. The triggering valve 32a is also connected through a branch line 45a to the charging valve (not illustrated) in the same manner as in the first embodiment.

The operation of this embodiment is as follows: the jacking actuators are operated to raise the plunger 16a with the triggering valve 32a open. At the point of the stroke, illustrated in FIGURE 2, when the seal 26a first engages the wall of the bore 21a a fluid connection is provided between the chamber 28a and cavity 18a through the open valve 32a. Therefore, continued upward movement of the plunger, until its upper end engages the end wall 22a, operates to pump charging gas out of the chamber 28a into the cavity 18a. When the plunger is in this topmost position, the volume of chamber 28a is at a minimum and the triggering valve 32a is closed. The jacking actuators are then retracted. This causes the plunger 16a to move downward increasing the volume of the chamber 28a until the pressure therein drops and the plunger 16a is pressure-suspended in a manner similar to the first embodiment.

The length of the bore 21a must be sufficiently long to permit the increase of the volume of the chamber 28a during this phase of operation a sufficient degree to reduce the pressure therein to a value which will produce pressure suspension or support of the plunger. When the jacking actuators are fully retracted, the triggering valve 32a can be opened to allow pressure to flow from the cavity 18a into the chamber 28a thus triggering the

plunger 16a and initiating its downward movement. Here again, as soon as the seal 26a moves out of the bore 21a, the full pressure in the cavity 18a acts on the plunger to produce a very high rate of acceleration toward its extended position. With this embodiment the requirement of a separate accumulator is eliminated while still retaining the desirable feature of eliminating all triggering losses of the charging gas.

In the embodiment of FIGURES 3 through 5, reference numerals referring to similar elements will be used with a "b" to indicate that the third embodiment is indicated. Hereagain, only the cap member 13 and the cooperating triggering and suspending structure is illustrated with the understanding that the remaining frame and jacking actuators will be the same as in the first embodiment. In this embodiment a check valve 58b is provided to connect the chamber 28b with the main cavity 18b. This check valve is arranged to permit flow in one direction only from the chamber 28b to the cavity 18b, and to prevent flow in the opposite direction. Hereagain, a triggering valve 32b is provided and the length of the bore 21b is arranged so that the plunger 16b can move downward from its extreme upper position to decrease the pressure in the chamber 28b so that the plunger can be fluid-supported in its cocked position.

In operation, upward movement of the plunger 16b carries the seal 26b into engagement with the wall of the bore 21b when the position of FIGURE 3 is reached. During this movement the valve 32b remains closed. As the plunger is moved upward between the position of FIGURE 3 and the position of FIGURE 4, reducing the volume of the chamber 28b to a minimum, the charging gas flows out of the chamber 28b through the check valve 58b into the main chamber 18b. Then, as the jacking actuators are retracted, the plunger 16b moves downward to the position of FIGURE 5 increasing the volume of the chamber 28b and causing the pressure therein to be greatly reduced. The check valve 58b prevents reverse flow and the triggering valve 32b is closed at this portion of the cycle. The plunger therefore remains in the position of FIGURE 5 until the triggering valve 32b is opened to admit charging gas into the chamber 28b and thus initiate downward movement of the plunger. This embodiment utilizing the check valve 58b again eliminates the necessity of a separate accumulator, but also eliminates the necessity of operating the triggering valve twice during the cycle. When the actuator is to be operated, the triggering valve 32b is opened to pressurize the chamber 28b and the plunger 16b moves to the extended position.

In the fourth embodiment of FIGURES 6 and 7, a "c" is added to reference numerals to indicate that reference is being made to the fourth embodiment. Hereagain, the complete machine would utilize a frame assembly 10 and jacking actuators in a manner similar to the first embodiment of FIGURE 1. In this embodiment a floating piston 59c is mounted in the cap 13c above the bore 21c. The cap is preferably formed with an enlarged bore 61c joined to the bore 21c by a radial shoulder 62c which serves as a stop to limit the downward movement of the floating piston 59c. A seal 63c on the floating piston 59c engages the wall of the bore 61c. A chamber 64c is therefore provided above the floating piston 59c and is connected through a port 66c to a valve 43c which is operable to selectively connect the chamber 64c to the pump 41c, the reservoir 42c, or isolate the chamber 64c from both the pump and the reservoir. Hereagain, the triggering valve 32c is operable to isolate the chamber 28c from the main cavity 18c or to provide free communication therebetween.

In this embodiment the chamber 28c is defined by the lower side of the floating piston 59c and the wall of the bore 21c in cooperation with the head of the plunger 16c. The valve 43c is operated to connect the chamber 64c to the pump 41c while the plunger is in its extended position and the minimum pressure is in the main cavity 18c.

This pressurizes the chamber 64c and pushes the floating piston 59c to its position against the shoulder 62c against the precharge pressure. The valve 43c is then closed to isolate the chamber 64c from both the pump and reservoir. Since liquid fills the chamber 64c, and liquid is substantially incompressible, the floating piston remains in its lower position as the plunger is raised by the jacking actuators. When the jacking actuators raise the piston 16c, the triggering valve 32c is closed and the plunger is raised to the position of FIGURE 6 at which time the seal 26c isolates the chamber 28c from the cavity 18c. The plunger is retained in this position and the valve 43c is operated to the position in which it connects the chamber 64c to the reservoir 42c thus exhausting the chamber 64c and allowing the floating piston to raise up to the position of FIGURE 7. This increases the volume of the chamber 28c and causes the pressure therein to be reduced. Normally the plunger 16c will raise slightly during the movement of the floating piston 59c until an equilibrium condition is reached wherein the pressure forces balance the weight of the plunger. This equilibrium condition may require some positive pressure in the chamber 28c depending upon the relative areas of the seals 26 and 17, the weight of the plunger and the pressure in the main cavity 18c.

When it is desired to trigger the plunger and initiate its downward movement, the triggering valve 32c is opened to provide communication between the chamber 28c and the main cavity 18c thus increasing the pressure in the chamber 28c and initiating the downward movement of the plunger. After the plunger reaches its extended position, the valve 43c is again operated to connect the chamber 64c to the pump 41c and cause the floating piston 59c to move down to the position in engagement with the shoulder 62c. This returns the system to its initial condition and again prevents any loss of charging fluid.

In all of these embodiments the chamber defined by the head of the plunger and the cap member is arranged so that the pressure can be reduced therein without loss of charging gas from the system. In each case the effective volume of the chamber 28 is increased to reduce the pressure and the support of the plunger by pressure forces is provided until the triggering valve is opened. Preferably, the triggering valve of each embodiment is provided with sufficient capacity to produce a pressure in the chamber 28 substantially equal to the pressure in the cavity 18 before the seal 26 moves out of the bore 21 so the seal will not be damaged.

Although preferred embodiments of this invention are illustrated, it is to be understood that various modifications and rearrangements of parts may be resorted to without departing from the scope of the invention as defined in the following claims.

I claim:

1. An actuator comprising a housing, a plunger slideable in said housing between first and second positions cooperating to define a cavity the volume of which is reduced by movement of said plunger to said first position, opposed walls on said housing and plunger proportioned to mate when said plunger is in said first position, seal means cooperating with said mating walls to define at least a portion of a chamber isolated from said cavity when said plunger is in said first position, valved means connected between said chamber and cavity selectively operable to isolate said chamber and cavity and to provide communication therebetween, compressible fluid under pressure in said cavity, and means operable to increase the volume of said chamber when said valved means are closed reducing the pressure thereof without releasing the fluid contained therein thereby producing pressure balancing of said plunger.

2. An actuator comprising a housing, a plunger slideable in said housing between first and second positions cooperating to define a cavity the volume of which is reduced by movement of said plunger to said first position, a first

10 seal between said plunger and housing having a first effective area, opposed walls on said housing and plunger proportioned to mate when said plunger is in said first position, second seal means cooperating with said mating walls to define at least a portion of a chamber isolated from said cavity when said plunger is in said first position, said second seal means having a second effective area greater than said first effective area, valved means connected between said chamber and cavity selectively operable to isolate said chamber and cavity and to provide communication therebetween, compressible fluid under pressure in said cavity, and means to increase the volume of said chamber when said valved means are closed reducing the pressure thereof without releasing the fluid contained therein, the pressure in said chamber being reduced to a pressure sufficiently low to produce a force on said plunger caused by said fluid under pressure maintaining said plunger in substantially said first position.

20 3. An actuator comprising a housing, a plunger slideable in said housing between first and second positions cooperating to define a cavity the volume of which is reduced by movement of said plunger to said first position, opposed walls on said housing and plunger proportioned to mate when said plunger is in said first position, seal means cooperating with said mating walls to define at least a portion of a chamber isolated from said cavity when said plunger is in said first position, valved means connected between said chamber and cavity selectively operable to isolate said chamber and cavity and to provide communication therebetween, fluid under pressure in said cavity, and an accumulator connected to said chamber operable to expand the fluid therein and reduce the pressure thereof without releasing the fluid, and pump means connected to said accumulator and operable to return fluid from said accumulator to said cavity.

25 4. An actuator comprising a housing, a plunger slideable in said housing between first and second positions cooperating to define a cavity the volume of which is reduced by movement of said plunger to said first position, opposed walls on said housing and plunger proportioned to mate when said plunger is in said first position, seal means cooperating with said mating walls to define at least a portion of a chamber isolated from said cavity when said plunger is in said first position, valved means connected between said chamber and cavity selectively operable to isolate said chamber and cavity and to provide communication therebetween, fluid under pressure in said cavity, and an accumulator including a pressure responsive member connected to said chamber movable under the influence of fluid pressure therein from an initial position to expand such fluid and reduce the pressure thereof without releasing such fluid, and means connected to move said pressure responsive member back to its initial position and return fluid to said cavity.

30 5. An actuator comprising a housing, a plunger slideable in said housing between first and second positions cooperating to define a cavity the volume of which is reduced by movement of said plunger to said first position, opposed walls on said housing and plunger proportioned to mate when said plunger is in said first position, seal means cooperating with said mating walls to define at least a portion of a chamber isolated from said cavity when said plunger is in said first position, valved means connected between said chamber and cavity selectively operable to isolate said chamber and cavity and to provide communication therebetween, gas under pressure in said cavity, and an accumulator connected to said chamber including a pressure responsive element dividing said accumulator into a gas section and a liquid section, said pressure responsive element being movable from an initial position under the influence of gas pressure in said chamber to increase the volume of such gas and reduce its pressure, and pump means connected to said accumulator and operable to supply liquid under pressure to said liquid

section and return said pressure responsive element to said initial position.

6. An actuator comprising a housing, a plunger slideable in said housing between first and second positions cooperating to define a cavity the volume of which is reduced by movement of said plunger to said first position, opposed walls on said housing and plunger proportioned to mate when said plunger is in said first position, seal means cooperating with said mating walls to define at least a portion of a chamber isolated from said cavity when said plunger is in said first position, valved means connected between said chamber and cavity selectively operable to isolate said chamber and cavity and to provide communication therebetween, fluid under pressure in said cavity, and an accumulator in said frame aligned with said chamber, a pressure responsive element in said accumulator open on one side to said chamber, said pressure responsive element being movable from an initial position under the influence of pressure in said chamber to increase its volume and decrease its pressure, and pump means connected to the other side of said pressure responsive element to move such element back to its initial position.

7. An actuator comprising a housing, a plunger slideable in said housing between first and second positions cooperating to define a cavity the volume of which is reduced by movement of said plunger to said first position, a bore in said housing, a head on said plunger positioned in said bore when said plunger is in said first position, seal means between said bore and head cooperating therewith to define at least a portion of a chamber isolated from said cavity when said plunger is in said first position, fluid under pressure in said cavity, a triggering valve operable to supply fluid under pressure to said chamber, and means operable to increase the volume of said chamber reducing the pressure thereof without releasing the fluid contained therein.

8. An actuator comprising a pair of telescoping members movable relative to each other between first and second positions and cooperating to define a fluid tight cavity the volume of which is reduced by movement of said members to said first position, a compressible fluid under pressure in said cavity normally urging said members toward said second position, said members cooperating to define at least a portion of a fluid tight chamber isolated from said cavity when said members are in said first position, means operable to increase the volume of said chamber without loss of fluid therein while said chamber is isolated from said cavity to reduce the pressure therein, said members being proportioned so that said members are retained substantially in said first position by fluid under pressure when the pressure in said chamber is reduced, and valved means operable to connect said cavity and chamber to increase the pressure in said chamber and cause pressure induced movement of said members to said second position.

9. An actuator comprising a cylinder, a plunger movable in said cylinder between first and second positions, said cylinder and plunger cooperating to define a cavity the volume of which is reduced by movement of said plunger to said first position, a compressible fluid under pressure in said cavity, said cylinder being formed with a blind bore, a head on said plunger positioned in said bore when said plunger is adjacent to said first position and operating to isolate a chamber defined by said bore and head from said cavity, valved means operable to permit flow of fluid from said chamber to said cavity as said head moves along said bore when said plunger moves to said first position, means operable to reduce the pressure in said chamber, said plunger and cylinder being proportioned so that said plunger is retained substantially in said first position by said fluid under pressure in said cavity when the pressure in said chamber is reduced, said valved means being operable to connect said cavity and chamber and increase the pressure in said chamber caus-

ing pressure induced movement of said plunger toward said second position.

10. An actuator comprising a cylinder, a plunger movable in said cylinder between first and second positions, said cylinder and plunger cooperating to define a cavity the volume of which is reduced by movement of said plunger to said first position, a compressible fluid under pressure in said cavity, said cylinder being formed with a blind bore, a head on said plunger positioned in said bore when said plunger is adjacent to said first position and operating to isolate a chamber defined by said bore and head from said cavity, valved means operable to permit flow of fluid from said chamber to said cavity as said head moves along said bore when said plunger moves to said first position, movement of said plunger from said first position toward said second position increasing the volume of said chamber and decreasing the pressure therein, said plunger and cylinder being proportioned so that said plunger is retained by pressure in said cavity substantially in said first position when the pressure in said chamber is decreased by movement of said plunger away from said first position, said valved means being operable to connect said cavity and chamber and increase the pressure in said chamber causing pressure induced movement of said plunger toward said second position.

11. An actuator comprising a cylinder, a plunger movable in said cylinder between first and second positions, said cylinder and plunger cooperating to define a cavity the volume of which is reduced by movement of said plunger to said first position, a compressible fluid under pressure in said cavity, said cylinder being formed with a blind bore, a head on said plunger positioned in said bore when said plunger is adjacent to said first position and operating to isolate a chamber defined by said bore and head from said cavity, a first valve operable to permit flow of fluid only from said chamber to said cavity, movement of said plunger from said first position toward said second position increasing the volume of said chamber and decreasing the pressure therein, said plunger and cylinder being proportioned so that said plunger is retained substantially in said first position by said fluid under pressure in said cavity when the pressure in said chamber is decreased by movement of said plunger away from said first position, and a second valve operable to connect said cavity and chamber and increase the pressure in said chamber causing pressure induced movement of said plunger toward said second position.

12. An actuator comprising a cylinder, a plunger movable in said cylinder between first and second positions, said cylinder and plunger cooperating to define a cavity the volume of which is reduced by movement of said plunger to said first position, a compressible fluid under pressure in said cavity, said cylinder being formed with a blind bore, a head on said plunger positioned in said bore when said plunger is adjacent to said first position and operating to isolate a chamber defined by said bore and head from said cavity, a check valve connected to permit flow of fluid only from said chamber to said cavity as said head moves along said bore when said plunger moves to said first position, movement of said plunger from said first position toward said second position increasing the volume of said chamber and decreasing the pressure therein, said plunger and cylinder being proportioned so that said plunger is retained substantially in said first position by said fluid under pressure in said cavity when the pressure in said chamber is decreased by movement of said plunger away from said first position, and a triggering valve operable to connect said cavity and chamber and increase the pressure in said chamber causing pressure induced movement of said plunger toward said second position.
